(57) **CLAIM**

The ornamental design for a modular floor panel locking system, as shown and described.

DESCRIPTION

FIG. 1 is a perspective view of a modular floor panel locking system, showing my new design;

FIG. 2 is an exploded perspective view thereof;

FIG. 3 is an exploded top plan view of FIG. 2;

FIG. 4 is an exploded bottom plan view of FIG. 2;

FIG. 5 is an exploded front elevational view thereof;

FIG. 6 is an exploded rear elevational view thereof;

FIG. 7 is an exploded left-side elevational view thereof; and,

FIG. 8 is an exploded right-side elevational view thereof.

The broken lines showing portions of the tiles depicted in the figures illustrate portions of the modular floor panel locking system that form no part of the claimed design. The dot-dash type broken line represents a boundary of the design.
